UNITED STATES PATENT OFFICE

135,277

DESIGN FOR A GLOVE DISPLAY STAND

Ardo L. Whisler, Port Huron, Mich.

Application January 9, 1943, Serial No. 109,224

Term of patent 14 years

To all whom it may concern:

Be it known that I, Ardo L. Whisler, a citizen of the United States, residing at Port Huron, in the county of St. Clair and State of Michigan, have invented a new, original, and ornamental Design for a Glove Display Stand, of which the following is a specification, reference being had to the accompanying drawings, forming part thereof.

I claim:

The ornamental design for a glove display stand, as shown.

ARDO L. WHISLER.
